FIG. 1.

INVENTOR.

Floyd M. Hagerman

BY

Malcolm W. Fraser

ATTORNEY

UNITED STATES PATENT OFFICE

2,488,534

EXERCISER

Floyd M. Hagerman, Swanton, Ohio

Application June 18, 1947, Serial No. 755,307

4 Claims. (Cl. 272—83)

1

This invention relates to exercisers, and an object is to produce a new and improved exerciser adapted to be mounted upon a side wall of a room and having handle means to be grasped by the person so that he is elevated slightly from the floor, spring means being provided yieldingly to resist the weight of the person, thereby to afford an exerciser for the spinal column, arm and shoulder muscles, etc.

Another object is to produce an exerciser which is simple in construction, can be readily mounted, has a minimum number of parts, is sturdy and reliable, and has the new and improved features of construction, arrangement and operation hereinafter described.

An embodiment of the invention is shown for purposes of illustration on the accompanying drawings, in which

Figure 1 is a front or face elevation partly in section, of the exerciser; and

Figure 2 is a side or end elevation of the exerciser.

The exerciser comprises a mounting bracket 10 preferably of metal or some sturdy material which is secured by screws 11 to the side wall of the room preferably somewhat above the reach of the person using it. Integral with the lower end of the bracket plate 10 and extending at approximately right angles outwardly therefrom is a plate 12 which is provided with a pair of longitudinally spaced apertures 13 through which vertically disposed rods 14 are freely slidable. The lower ends of the rods 14 are screw-threaded to engage a grip member 15. The grip member 15 is made up of a pair of loop members 16, each having a rubber hand grip 17 and the two loop members 16 are integrally connected by a web 18.

The upper end of each rod 14 has a head 19 against which a centrally embossed portion 20 of a stop plate 21 bears. Abutting against the under side of each stop plate 21 is a helical coil spring 22, the lower end of which bears against a metal washer 23 which rests against the upper side of an outwardly extending bumper flange 24. The lower face of the bumper flange 24 is adapted to bear against the upper surface of the bracket plate 12. Integral with the flange 24 is an inwardly tapering bumper element 25. The bumper 25 and its flange 24 in each case are formed with a central aperture 26 through which the respective rod 14 freely slides.

Each spring 22 is enclosed by a cylindrical metallic casing 27, the inside diameter of which is slightly greater than the diameter of the spring, the casing providing a guide for the respective

2

spring. The lower end of each casing 27 is formed with an inwardly extending flange 28 against which the bumper flange 24 rests. In this manner, each casing 27 is held in place by the bumper flange 24 which in turn is held in place by the respective coil spring 22.

In use, the device being mounted slightly beyond the person's reach, the person can hang by his hands engaging the handle grips 17 and in such suspended position, the weight of the body will tend to pull on the spinal column. In addition, it is manifest that the muscles of the arm, shoulders and back may be exercised. By having the body suspended in this manner, the person, by his own effort, can effect a jumping action, thereby causing the coil springs to expand to take up the upward movement of the body and yieldingly resist the downward body movement, this recurrently taking place and enabling the person to effect the desired flexing of the muscles and a certain tensioning of the spinal column.

From the above description, it will be manifest that I have produced an exceedingly simple exercising device, which can be produced inexpensively and is sturdy and reliable in construction. An outstanding feature resides in the extreme simplicity by which the parts can be assembled without the use of special tools and the manner in which the spring elements retain certain parts in the desired assembled position.

It is to be understood that numerous changes in details of construction, arrangement and operation may be effected without departing from the spirit of the invention especially as defined in the appended claims.

What I claim:

1. An exerciser of the class described, comprising a mounting bracket adapted to be secured to a wall surface, an outwardly extending plate rigid with said bracket having an aperture, a slidable rod extending through said aperture, a hand grip secured to one end of said rod on one side of said plate, a stop plate on the opposite end of said rod, a coil spring encircling said rod and bearing at one end against said stop plate, a rubber bumper apertured slidably to receive the rod therethrough, and against which said stop plate is adapted to abut upon compression of said spring, and an outwardly flanged portion on the lower end of said bumper bearing against said plate on the outer side, the inner side of said flanged portion being adapted to receive the opposite end of said spring, thereby to retain the bumper in place.

2. An exerciser of the class described, comprising a mounting bracket adapted to be secured to a wall surface, an outwardly extending plate rigid with said bracket having an aperture, a slideable rod extending through said aperture, a hand grip secured to one end of said rod on one side of said plate, a stop plate on the opposite end of said rod, a coil spring encircling said rod and bearing at one end against said stop plate, a rubber bumper apertured slidably to receive the rod therethrough, and against which said stop plate is adapted to abut upon compression of said spring, an outwardly flanged portion on the lower end of said bumper bearing against said plate on the outer side, the inner side of said flanged portion being adapted to receive the opposite end of said spring, thereby to retain the bumper in place, and a tubular casing fitting said spring, the inner end of the casing being inwardly flanged and such flange being disposed between the bumper flanged portion and the plate.

3. An exerciser as claimed in claim 2, comprising a metallic washer interposed between the inner side of the flanged bumper portion and the spring, and the bumper tapering inwardly from the flanged portion thereof to augment the cushioning action thereof when engaged by the stop plate.

4. An exerciser of the class described, comprising a mounting bracket adapted to be secured to a vertical wall surface, a plate rigid with said bracket and extending at substantially right angles therefrom, said plate having a pair of apertures spaced longitudinally from each other, a rod slideable in each aperture, a hand grip secured to the lower end of each rod respectively, a rigid connection between said hand grips, a stop plate on the upper end of each rod, a coil spring encircling said rod and bearing at one end against said stop plate, a rubber bumper for each rod and concentric therewith, each bumper having a vertical aperture through which the respective rod is slideable, a lower flanged end on said bumper, a metal washer on the upper side of said flanged end to provide a bearing for the lower end of the respective spring, a casing for each coil spring, and an inwardly extending flange on the lower end of each casing disposed between the adjacent bumper flange and said rigid plate.

ing a mounting bracket adapted to be secured to a vertical wall surface, a plate rigid with said bracket and extending at substantially right angles therefrom, said plate having a pair of apertures spaced longitudinally from each other, a rod slideable in each aperture, a hand grip secured to the lower end of each rod respectively, a rigid connection between said hand grips, a stop plate on the upper end of each rod, a coil spring encircling said rod and bearing at one end against said stop plate, a rubber bumper for each rod and concentric therewith, each bumper having a vertical aperture through which the respective rod is slideable, a lower flanged end on said bumper, a metal washer on the upper side of said flanged end to provide a bearing for the lower end of the respective spring, a casing for each coil spring, and an inwardly extending flange on the lower end of each casing disposed between the adjacent bumper flange and said rigid plate.
